[57] ABSTRACT

A method for securing a strap to a buckle formed of non-resilient material and the buckle and strap construction resulting therefrom, said buckle being constituted by two side pieces joined by two end cross pieces and two spaced central cross pieces with oppositely facing serrated edges defining a slot therebetween, said method comprising threading the strap through the serrated slot and thereafter compressing the central pieces toward each other to firmly grip and secure the strap.

FIG. 1

FIG. 2

FIG. 3

BUCKLE-STRAP CONSTRUCTION

CROSS-REFERENCE TO RELATED APPLICATION

This application is a continuation-in-part of U.S. Pat. application Ser. No. 333,014, filed Feb. 16, 1973, now abandoned.

BACKGROUND OF THE INVENTION

This invention relates to a method for assembling a buckle-strap construction which insures that the strap is fixedly secured to the buckle as well as to the resulting buckle-strap construction.

In the manufacture of strap and buckle assemblies for use with garments, undergarments such as brassieres, and the like, it is recognized that a portion of the strap should be firmly secured to the buckle to prevent slippage or creep of the buckle and/or strap as well as to permit strap length adjustability. It is further required that the buckle construction and the method for securing the strap thereto be readily applicable to a wide variety of straps regardless of strap thickness. In the past, straps have been secured to the buckle merely by manipulating a portion of the strap in and around a central buckle slot. Such a technique does not, however, provide a permanent connection, there being the distinct possibility of the strap unraveling on the buckle and thereby destroying the effectiveness of the strap and buckle assembly. Other securing techniques have included passing the strap through the central slot and then stitching, laminating or otherwise attaching the end of the strap to other parts thereof as well as applying beads, folds, clips or other bulk means to the end of the strap to prevent its being pulled back through the buckle. However, these techniques are also disadvantages insofar as they do not provide tight, effective locking of the strap while frequently causing unsightly and irritating bulk in the area of the buckle.

A further method for securing the strap to a buckle is disclosed in U.S. Pat. No. 3,192,587, White. This technique utilizes a buckle which has a central strap slot and which is formed of a resilient plastic material. The cross bars defining the strap slot are then elastically spread apart to a width greater than the thickness of the strap, the strap threaded through the spread bars and the bars then released to grip the strap. The difficulties which may be encountered with this procedure includes the possibility that the plastic bars may tend not to return to their original position subsequent to spreading thereby providing insufficient gripping pressure on the strap, that the resilient bars may be subjected to inadvertent spreading as a result of laundering or normal handling thereby freeing the strap, and that the plastic itself may not be able to supply sufficient pressure to firmly grip the strap. With each of these occurrences, the primary characteristic of the assembly may be nullified.

It is the prime object of this invention to provide a strap and buckle construction of the type described in which the strap is firmly secured to the buckle.

It is a further object to provide an improved method for securing a portion of the strap to a buckle.

It is still a further object to provide a buckle construction suitable for use with the latter method.

It is another object to provide such an improved method which is generally applicable to a wide variety of strap thicknesses.

SUMMARY OF THE INVENTION

In accordance with this invention, a method is provided for firmly securing a strap to a buckle wherein the strap is threaded through a central slot defined by two spaced serrated cross pieces and the cross pieces are then compressed toward each other to firmly grip the strap. In order to accomplish this improved technique, a buckle construction is provided which is formed of a non-resilient material and which is constituted by two side pieces joined by two end cross pieces and two spaced central cross pieces with oppositely facing serrated edges defining a slot therebetween which is wider than the thickness of the slot.

15 This buckle construction when utilized in conjunction with the specified method substantially overcomes the disadvantages of the prior art constructions and assembling techniques. Thus, the strap is firmly and substantially permanently secured without the need for any extraneous attachments such as beads or clips. The predetermined enlarged width of the central strap-receiving slot permits satisfactory engagement with a wide variety of strap regardless of their thickness. The utilization of a non-resilient material for the buckle construction permits the permanent compression of the central cross pieces and eliminates the possibility of any inadvertent spreading thereof during laundering or conventional handling. In this manner, the instant approach is also a significant improvement over the 20 White technique. Thus, by utilizing a non-resilient buckle material and a compression step rather than a resilient plastic material and an expansion step, the instant approach avoids any reliance on the inherent ability of the buckle material to return to its original gripping configuration or to exert sufficient natural pressure to effectively secure the strap. It indeed provides an affirmative, controllable approach to the problem.

BRIEF DESCRIPTION OF THE DRAWING

To the accomplishment of the above, and to such other objects as may hereinafter appear, the present invention relates to a buckle-strap construction and method of assembling same as defined in the appended claims and as described in this specification, taken together with the accompanying enlarged drawings, in which:

FIG. 1 is a perspective view of a buckle applicable to the present invention;

FIG. 2 is a top plan view of the buckle and strap assembly of this invention;

FIG. 3 is a cross sectional view of the assembly of FIG. 2, taken along line 3-3 thereof;

FIG. 4 is a top plan view of a buckle applicable to a second embodiment of the present invention; and

FIG. 5 is a top plan elevational view of the buckle and strap assembly of the second embodiment of the present invention.

DETAILED DESCRIPTION OF THE PREFERRED EMBODIMENTS

FIG. 1 depicts a buckle applicable to the instant invention. It is seen that buckle 10 is essentially planar and is formed, as by a stamping technique, of a one-piece non-resilient material such as a metal-like aluminum or steel. Buckle 10 is constituted by two side pieces 12, 14 which are joined at the ends thereof by two end cross pieces 16, 18 and intermediate the ends

by two central cross pieces 20, 22 thus defining central strap slot 24 and outer strap slots 26, 28. The opposing facing edges 30, 32 of cross pieces 20, 22 are serrated to provide a firmer grip on the subsequently secured strap. Central strap slot 24 is formed to exhibit a width at least equal to and usually greater than the thickness of conventional garment straps thereby to accommodate a large variety of straps exhibiting a diversity of strap thicknesses. For example, a slot width of approximately 3/32 inch was found to accommodate substantially all conventional strap thicknesses.

The manner in which a strap is firmly secured to the buckle is depicted in FIG. 2. Thus, garment strap 34 is threaded through buckle 10 by inserting a free end 36 of strap 34 between cross pieces 20, 22 through slot 24, the width of slot 24 being greater than the thickness of strap 34. Once the appropriate length of strap 34 has passed through slot 24, cross pieces 20, 22 are compressed toward each other in the direction of A and B generally in the plane of buckle 10 until serrated edges 30, 32 firmly grip strap 34. Compression may be accomplished manually as by means of a pair of pliers or the like, or by means of automated compressing machinery. In either event, cross piece 20, 22 will retain their deformed configuration ensuring the substantially permanent attachment of strap 34 to buckle 10.

The general threading of strap 34 through buckle 10 may be then determined by the practitioner in accordance with his particular requirements, the manner of threading forming no part of the instant invention. A typical threading approach is depicted in FIGS. 2 and 3 wherein the free end 36 of strap 34 is passed through slot 28, over cross piece 22, through central slot 24, and under cross piece 20. The other portion of strap 34 is continued through a support member (not shown), looped back under end piece 18, through slot 28, over cross piece 22, slot 24 and cross piece 20, then through slot 26 and under end piece 16. In this manner, the strap is firmly secured in the buckle while being readily adjustable to provide various strap lengths. Such adjustment may be made merely by loosening the load on the buckle and then shifting it in the desired direction.

Referring now to FIGS. 1 and 2 in particular, the first embodiment of the present invention shown therein has not been found to be entirely satisfactory in use due to a weakening of the buckle construction at the connection points 40, 42, 44, 46 of the central cross pieces 20, 22 to the side pieces 12, 14 after the central cross pieces 20, 22 are compressed towards each other. The weakening at the connection points 40-46 is believed to result from the non-linearity of the central cross pieces 20, 22 in the finished assembly, and more particularly the non-linearity of the non-serrated edge of the central cross piece 22 which must resist the bulk of the transverse pressure applied during use by the garment strap 34 and tending to pull the central cross piece 22 from its connection points 44, 46 with the side pieces 12, 14. A further and related disadvantage of the first embodiment is the failure of the convexly bowed serrated edges 30, 32 of the central cross pieces 20, 22 to grasp the garment strap 34 therebetween with equal pressure along the entire width of the strap 34 due to the convex bowing of the central cross pieces 20, 22 during the compression step. Thus, as the forces applied to the strap 34 by the serrated edges 30, 32 are not evenly distributed along the width of (and so tend to cause tearing of) the strap 34, the buckle 10 must ei-

ther be constructed of an oversize width so as to enable grasping of the garment strap 34 only between the relatively parallel central portions of the central cross pieces 20, 22 or, in the alternative, the strap 34 must be formed of a more tear-resistant material than would otherwise be required. Still another related disadvantage of the first embodiment was a tendency of the concave non-serrated edges of the central cross pieces 20, 22 to cause fraying of the outer edges of a relatively non-elastic garment strap 34 in slots 26, 28, adjacent the connection points 40-46, as such strap edges received a disproportionately high proportion of the stress being applied to the garment strap 34 (and in particular the concave non-serrated edges of the central cross piece 22 caused fraying of the garment strap 34 in slot 28 adjacent the connection points 44, 46).

Referring now to FIGS. 4 and 5, the second embodiment of the present invention illustrated therein is similar to the first embodiment, but avoids the aforementioned disadvantages thereof by providing in the stamped piece shown in FIG. 4, cutouts or notches 48, 50, 52, 54, along the non-serrated edges of the central cross pieces 20, 22 adjacent each of the connection points 40-46 of the central cross pieces 20, 22 with side pieces 12, 14. The above referenced non-serrated edges may also be referred to, both before or after the compression step, as "non-engaging" edges as such edges do not engage the portion of garment strap 34 within the central strap slot 24, or, before the compression step, as "non-linear non-engaging edges" as the cut outs 48-54 interrupt any linearity of such edges prior to collapse of the cut outs. These edges participate in a definition of the outer strap slots 26, 28, just as the serrated edges 30, 32 participate in the definition of the central strap slot 24. Preferably the cut-outs 48-54 are generally semi-circular in configuration and extend about halfway through the cross pieces 20, 22, as shown in FIG. 4, while the non-serrated edges of the cross pieces 20, 22 are substantially linear between the cut-outs at each end, also as shown in FIG. 5. Alternatively, however, each cut-out may be configured as a "U", "V" or other shape convenient for stamping operations and may extend more or less than halfway through the cross piece; also, the non-serrated edge between the cut-outs need not be linear, provided in all cases that the results described hereinafter are obtained during the compression step. When the central cross pieces 20, 22 are subsequently compressed towards one another, they assume the configuration shown in FIG. 5 with the non-serrated edges being substantially linear along the entire width between side pieces 12, 14 and the serrated edges 30, 32 grasping the garment strap 34 with substantially equal force along the entire width thereof through central slot 24. A comparison of the cross pieces 20, 22 in FIGS. 4 and 5 (representing the buckle before and after the compression step, respectively) shows that the substantially non-linear non-engaging edges of the cross pieces 20, 22 prior to the compression are more linear afterwards and the initial cut-outs 48-54 are collapsed after the compression step, that is, they are substantially reduced in depth and, in fact, less detectable due to the movement of the cross pieces relative to the connection points 40-46 of the buckle 10.

Provision of the cut-outs 48-54 reduces slightly the amount of material required to construct the buckle 10 (thereby also slightly reducing the weight and manufac-

turing cost of the buckle 10), substantially eliminates any tearing of the garment strap 34 by more equally distributing the grasping force along the width of the garment strap 34, greatly reduces the likelihood of breakage of central cross pieces 20, 22 at the connection points 40-46, and significantly reduces fraying of the outer edges of garment strap 34 by more equally distributing the forces applied by the non-serrated edges of the central cross pieces 20, 22 along the entire width of the garment strap 34.

Summarizing, it is seen that the improvement in the novel buckle and strap assembly of the present invention are primarily attributable to the use of a non-resilient material in forming the buckle and to the compression of the cross pieces defining the central strap-receiving slot. Thus, the strap is firmly secured between the compressed cross pieces, the non-resiliency thereof insuring the retention of the cross pieces in their compressed configuration. A further improvement is attributable to the cut-outs in the uncompressed buckle at either end of the central cross pieces where the non-engaging edges thereof join the side pieces.

While the invention has been described in terms of the specific embodiments herein, it should be apparent that variations may be developed without departing from the spirit or scope of the invention as defined by the following claims.

We claim:

1. A buckle and strap assembly comprising a buckle formed of essentially non-resilient deformable material and having a pair of elongated side pieces, a pair of cross pieces joining said side pieces intermediate their ends and having inner edges defining a strap slot therebetween, and a strap inserted through said strap slot, said cross pieces being bent inwardly toward one another thereby to engage and firmly secure said strap, at least one of said cross pieces having a non-engaging outer edge defining a continuous and substantially lin-

ear surface throughout its major portion and including adjacent each end thereof a notch in a substantially collapsed condition.

2. The assembly of claim 1 wherein said non-engaging edge has a collapsed notch at each end thereof.

3. The assembly of claim 1 wherein both of said cross pieces have substantially linear non-engaging edges.

4. The assembly of claim 1 wherein said cross pieces engage said strap substantially uniformly along the width of said strap slot.

5. In a buckle for use in a buckle and strap assembly comprising

A. a pair of elongated side pieces;

B. a pair of end cross pieces joining the ends of said side pieces; and

C. a pair of central cross pieces joining said side pieces intermediate said ends thereof, each of said central cross pieces having

i. an inner edge facing the other of said central cross pieces to define a central slot therebetween adapted to engagingly receive a strap threaded therethrough when said central cross pieces are compressed towards one another about the strap; and

ii. an outer edge facing one of said end cross pieces to define an outer strap slot therebetween;

the improvement wherein said buckle is formed of essentially non-resilient deformable material and said outer edges of said central cross pieces include notches at the junctures thereof with said side pieces and are essentially continuous and linear intermediate said notches, said notches being adapted to be collapsed during compression of said central cross pieces.

6. The buckle of claim 5 wherein said inner edges of said central cross pieces are serrated.
